COMBINED FOUNTAIN AND SEAT FOR SWIMMING POOLS AND THE LIKE

Joseph D. George, 1263 Royal York Road,
Islington, Ontario, Canada

Filed July 11, 1963, Ser. No. 75,754

Term of patent 14 years

(Cl. D91—4)

FIGURE 1 is a perspective view of a combined fountain and seat for swimming pools and the like, showing my new design.

The side opposite that shown in FIG. 1 is a mirror image thereof.

I claim:

The ornamental design for a combined fountain and seat for swimming pools and the like, substantially as shown and described.
